UNITED STATES PATENT OFFICE.

LOUIS BURGER, OF CHICAGO, ILLINOIS.

DESIGN FOR A SPOON.

SPECIFICATION forming part of Design No. 22,256, dated March 7, 1893.

Application filed January 3, 1893. Serial No. 457,173. Term of patent 3½ years.

To all whom it may concern:

Be it known that I, LOUIS BURGER, a citizen of the United States, residing at Chicago, county of Cook, and State of Illinois, have invented and produced a new and original Design for Souvenir Spoons, &c., of which the following is a specification, reference being had to the accompanying drawing, which is a fair illustration thereof.

10 The leading feature of my design consists of the handle as illustrated in the drawing, the end or head portion of which is in the form of a crown, adjacent to which crown the handle has a tapered outline and has marked upon 15 it the representation of a woman. The edges of the tapered outline are in the form of rep-

resentations of unfurled flags, the staffs of which form the marginal outlines or frame lines of the picture. The remainder of the handle is composed of outline representations 20 of a man with arms elevated, represented as supporting a globe, which is marked with lines as illustrated.

What I claim as new, and desire to secure by Letters Patent, is—²⁵

The design for the handle of souvenir spoons, &c. substantially as herein shown and described.

LOUIS BURGER.
